UNITED STATES PATENT OFFICE.

FREDERICK J. WILLOCK, OF RICHMOND HILL, NEW YORK.

DESIGN FOR A TABLE ORNAMENT OR ANALOGOUS ARTICLE.

Application filed September 2, 1927. Serial No. 23,275. Term of patent 3½ years.

To all whom it may concern:

Be it known that I, FREDERICK J. WILLOCK, a citizen of the United States, and a resident of Richmond Hill, county of Queens, and State of New York, have invented a new, original, and ornamental Design for a Table Ornament or Analogous Article, of which the following is a specification, reference being had to the accompanying drawing, forming a part hereof.

The figure in the drawing shows a per-

spective view of the table ornament or analogous article.

The dominant feature of the design consists in an airplane A surmounting a dome B. The dome is ornamented to simulate clouds and water.

I claim:

The ornamental design for a table ornament or analogous article substantially as shown and described.

FREDERICK J. WILLOCK.
